UNITED STATES PATENT OFFICE.

RICHARD SCHULZ, OF BERLIN, GERMANY.

FEED-WATER REGULATOR FOR BOILERS.

SPECIFICATION forming part of Letters Patent No. 683,148, dated September 24, 1901.

Application filed May 3, 1900. Serial No. 15,389. (No model.)

To all whom it may concern:

Be it known that I, RICHARD SCHULZ, a subject of the King of Prussia, residing at Berlin, Germany, have invented certain new and useful Improvements in Feed-Water Regulators for Boilers; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has relation to appliances for controlling the supply of water to steam-boilers; and it has for its object the provision of simple means whereby the supply of water to a steam-boiler may be readily controlled and the controlling appliances rendered inoperative under certain conditions or whenever this becomes desirable or necessary; but that my invention may be fully understood I will describe the same in detail, reference being had to the accompanying drawings, in which—

Figures 1, 2, and 3 are longitudinal sectional views of the feed-water regulator, showing the regulating-valves in different positions. Figs. 4, 5, and 6 are end views showing the adjusting-lever in the positions corresponding with the respective positions of the valve-spindle in Figs. 1, 2, and 3. Fig. 7 is a sectional view of a steam-boiler having the feed-water regulator applied thereto, and Fig. 8 is a cross-section on line $x-x$ of Fig. 1.

The regulator comprises a valve-casing a , having an internal water-distributing chamber a , into which opens the supply branch b , said chamber having in each of its opposite walls in the axial line of the casing an inlet-port controlled by valves $b-b'$ on a valve-spindle h . One end of this spindle h is screw-threaded and screwed into a sleeve c , provided with a perforated lug c' , adapted to be connected by a rod d to a lever pivoted on a standard in the boiler B , to which lever the float-rod d is secured in a well-known manner. The sleeve c has a stop-flange g , abutting against a circular abutment in the casing a , to which the sleeve c is keyed or feathered, so as to prevent its rotation in its bearing f without interfering with its longitudinal or endwise movements. The casing a has a flange a^2 , by means

of which it is bolted to the boiler at a proper point, and a^3 is the feed-water-discharge branch. The outer end of the valve-spindle h is connected to an adjusting or regulating spindle k by means of a key or pin k' , passing through a longitudinal slot k^2 in said spindle k , so that when the latter is revolved the valve-spindle will also be revolved and screwed into or out of its sleeve c , according to the direction of rotation of spindle k , which latter is prevented from partaking of the longitudinal motion of the valve-spindle h . The spindle k has its bearings in suitable stuffing-boxes and projects from the casing a , the outer end of the spindle being attenuated and screw-threaded, as shown at k^3 , and on said attenuated end of the spindle is mounted a hand-lever i , provided with a pointer i' , traveling over a scale i^2 on the outer face of casing a . The lever i is or may be an integral part of a sleeve s , fitted in a suitable bearing at the outer end of a casing a , the interior of the sleeve s being of polygonal form in cross-section and fitting a corresponding portion k^4 on spindle k , and on the attenuated threaded portion k^3 of said spindle works a lock-nut k^5 , provided with a handle k^6 for locking the spindle k against rotation when revolved for adjustment of valve-spindle h . In practice to afford access to all parts of the regulator I prefer to construct the casing in sections—namely, of a body part a , having the flange a^2 at one end and a flange a^7 at the opposite end, the branch a^3 , screwed or otherwise secured to said body part, the head-plate a^8 , provided with a recess or stuffing-box for the gland o and screwed into said body part a , and the outer part a^9 , bolted to the head-plate a^8 and having at its outer end the scale-face i^2 and a bearing a^8 for the sleeve s , so that the regulator can be readily dismembered. Although I prefer to bolt or otherwise secure the regulator-casing to the boiler, as described and shown, it is obvious that the casing may be located outside of or wholly within the boiler.

From the above description it will be readily understood that the position of the float e , hence the height of the water-level in the boiler, is determined by the length of the connections between the valve-stem and the float-actuated lever, since it is obvious that the longer these connections the higher will the

float be held, and hence the higher will be the water-level, the float being prevented from rising beyond its adjusted position by the stop-flange g and the abutment about the bearing 5 for the sleeve c , while the drop of the float is limited by the length of the slot k^2 in the adjusting-spindle. In other words, by varying the length of the connections between the valve-spindle and the float-actuating lever 10 the angular relation of the float-rod relatively to the valve-spindle and connecting-rod is correspondingly varied. When the connection between the valve-spindle h and connecting-rod d' is shortest—that is to say, when 15 the spindle is fully screwed into its sleeve c —the rods d', d are substantially parallel and the float e will be held in its lowermost position, corresponding, therefore, to the lowest water-level in the boiler, the pointer i' of lever i on scale i^2 being then on the first graduation on the left of the scale i^2 , Fig. 4, the spindle h being free to reciprocate as the float e falls and rises by reason of the pin-and-slot connection of the valve-spindle with the adjusting-spindle k , thereby opening or closing 20 the inlet or feed ports in chamber a' . If now, say, a quarter-turn be given to lever i and therethrough to spindles k and h from left to right, the pointer being midway on 25 the scale, Fig. 5, the said valve-spindle h will be partly screwed out of its sleeve c , Fig. 2, lengthening to that extent the connection between such spindle and the connecting-rod d' , thereby raising the float e to a correspondingly higher level, the valve-spindle still having sufficient longitudinal motion to move 30 the valves b and b' to and from their seats, this being the case in whatever position the lever i may be moved, except when moved to its extreme position to the left, Figs. 3 and 35 6, the pointer being then on the last graduation of said scale on the right. When the lever i is moved to the position last referred to, the valve-spindle h will have been screwed out 40 of its sleeve c to such an extent as to bring the key or pin k' , that connects said spindle with the adjusting-spindle k , to the outer end of its slot k^2 , with the flange g of the sleeve bearing on its abutment and locking the valve-spindle against motion, with both valves off 45 their seats, as shown in Fig. 3. Obviously the flange g determines the position of the float in the boiler and prevents said float from rising beyond the position to which it is adjusted, and obviously the height of the water-level in the boiler may by the means described be varied from a minimum to a maximum level, dependent upon the extent to 50 which the length of the connection between the spindle and connecting-rod d' can be increased from a minimum length. The length of the slot k^2 in the spindle k is equal to twice the throw of the valve-spindle, said spindle having twice the required throw when in its 55 relation with the sleeve c , as shown in Fig. 1, the amplitude of the throw of the spindle being gradually reduced as it is screwed out of

said sleeve and is *nil* when screwed out to the full extent, in which position the valves b and b' , as above stated, are held off their seats, the regulator being thrown out of operation by the means which control the height of the water-level in the boiler. Such an arrangement is if not absolutely necessary yet very desirable, as it affords means for feeding the boiler in the ordinary manner, which is generally required of reliable boilers. Although I have shown the feed-water-distributing chamber a' as provided with two distributing or outlet ports, it is obvious that but one may be used. 70 75 80

From the description of the construction and operation of the feed-water regulator it will be readily seen that the supply of water to the boiler is not regulated as usual by increasing or decreasing the volume flowing to the boiler, such increase or decrease being determined by the throw of the valve, which latter is determined by the amplitude of the rising and falling movements of a float. In 85 my said feed-water regulator the volume of water flowing to the boiler is always the same whatever the throw of the valve or the amplitude of the rising and falling movements of the float may be, the supply being regulated 90 solely by an absolute cut-off determined by the amplitude of the movements of the valve and float. 95

Having thus described my invention, what I claim as new therein, and desire to secure by Letters Patent, is—

1. A feed - water regulator, comprising a valve-casing having a feed branch and a feed-water-distributing chamber having ports in its opposite walls, a valve for each of said ports, a valve-spindle common to both valves and having endwise motion in the valve-casing, an internally-threaded sleeve into which said spindle is screwed, said sleeve held against rotation but moving endwise with the spindle, and means for revolving the spindle without interfering with its endwise movement, whereby said spindle may be screwed more or less into or out of said sleeve; in combination with a float-reciprocated rod connected with the sleeve, substantially as and for the purpose set forth.

2. A feed - water regulator, comprising a valve-casing having a feed branch, and a feed-water-distributing chamber having ports in its opposite walls, a valve for each of said ports, a valve-spindle common to both valves and having endwise motion in the valve-casing, an internally-threaded sleeve into which said spindle is screwed, said sleeve held against rotation but moving endwise with the spindle, means for revolving the spindle without interfering with its endwise movement whereby said spindle may be screwed more or less into or out of said sleeve, and means limiting the movements of the spindle in either direction; in combination with a float-reciprocated rod connected with the sleeve, substantially as and for the purpose set forth.

3. The combination with the valve-spindle *h*, the valve-casing and the sleeve *c* into which the spindle is screwed, said sleeve held against rotation but having endwise motion in the casing, and said spindle provided with a slot *k*²; of the spindle *k* connected with the valve-spindle by a pin passing through the aforesaid slot, and means for revolving the spindle *k*, substantially as and for the purpose set forth.

4. The combination with the valve-casing *a* having a graduated index on its outer face, the valve-spindle *h* having rotary and endwise motion in said casing and provided with an elongated slot *k*², and the sleeve *c* screwed to the valve-spindle and having a perforated lug, said sleeve held against rotation in its

bearing but free to move endwise with the valve-spindle; of the revoluble spindle *k* having a bearing of polygonal form in cross-section, a sleeve fitting said bearing and provided with a handle *i* and pointer *i'* adapted to travel over the aforesaid scale, and a lock-nut for locking the spindle *k* against rotation, substantially as and for the purpose set forth.

In testimony that I claim the foregoing as my invention I have signed my name in presence of two subscribing witnesses.

RICHARD SCHULZ.
